UNITED STATES PATENT OFFICE.

MICHAEL D. COX, OF KNOXVILLE, ASSIGNOR OF ONE-HALF TO J. R. McCALLUM,
OF KNOX COUNTY, TENNESSEE.

CAR-COUPLING.

SPECIFICATION forming part of Letters Patent No. 403,461, dated May 14, 1889.

Application filed March 8, 1889. Serial No. 302,560. (No model.)

To all whom it may concern:

Be it known that I, MICHAEL D. COX, a citizen of the United States, residing at Knoxville, in the county of Knox and State of Tennessee, have invented certain new and useful Improvements in Car-Couplings, of which the following is a description.

My invention consists of an improved railroad-car coupler and draw-head, which constitutes a self-coupler, and which consists of the defined construction of parts hereinafter set forth and claimed, reference being had to accompanying drawings and the letters marked thereon, making a part of this specification; and in order to enable others to understand and operate the same I will now proceed to describe its construction and operation, referring to the annexed drawings, in which—

Figure 1 is a perspective view of a railroad-car draw-head with arrangements for coupling attached. Fig. 2 is a transverse vertical section of the same, showing the position of coupling device when ready for coupling.

Fig. 3 is also a transverse vertical section of the same, showing coupling device when coupled. Fig. 4 is an iron frame with spring attached for holding coupling-pin in position for coupling. Fig. 5 shows the front edge of the rear part of the spring-frame, with countersunk hole for receiving the rivet or screw-head. Fig. 6 shows the rear edge of the same. Fig. 7 shows the bolt or rivet holding the spring to spring-frame. Fig. 8 shows a side view of coupling-pin, with notch B, which receives spring-frame when holding pin in proper position for coupling, also showing shoulder C, which rests on coupling-link, holding it in a horizontal position to receive the

other coupling. Fig. 9 shows a front view of coupling-pin. Fig. 10 shows a rear view of same.

In order to operate this coupling, press spring-frame A back into the slot-hole in the upper part of the draw-head, place coupling-link in position, and drop coupling-pin in the oblong square hole D, when the shoulder C will descend and rest on coupling-link, holding same in a horizontal position to receive the other coupling. Then on the other draw-head raise coupling-pin till the spring-frame catches in notch B, as shown in Fig. 2, which holds coupling-pin in position for coupling. When the two draw-heads come together, spring-frame A, as shown in Fig. 2, will be pressed back, as shown in Fig. 3, thereby relieving the coupling-pin, which will drop into position, as seen in Fig. 3, thereby completing the coupling.

In order to uncouple, raise coupling-pin till spring-frame A catches in notch B, which securely holds coupling-pin in the proper position for future coupling.

Having therefore fully described my invention, what I claim as new, and desire to secure by Letters Patent, is—

In a car-coupling, the combination of the oblong frame provided with the spring and the pin provided with the shoulder and the notch B, all substantially as described.

In testimony that I claim the foregoing I have hereunto set my hand this 19th day of February, 1889.

MICHAEL D. COX.
